DEVICE FOR DESTROYING VERMIN

Lydia Cook, Burlington, Iowa

Application March 14, 1932. Serial No. 598,843

3 Claims. (Cl. 43—123)

My invention relates to improvements in electrical vermin exterminators.

An important object of the invention is to provide a device which will serve as a protector for the floor, or the like, so that the floor will not be damaged by the castor or leg of the bed and which will also serve to exterminate the bed bugs.

In the accompanying drawing, forming a part of this specification, and in which like numerals 10 are employed to designate like parts throughout the same,

Figure 1 is a side elevation of a device embodying my invention, parts in vertical section,

Figure 2 is a plan view of the same, the cover 15 element being shown in section,

Figure 3 is an end elevation of one unit of the device, and,

Figure 4 is a vertical section through a receptacle included in the device.

20 In the drawing, wherein for the purpose of illustration is shown a preferred embodiment of my invention, the numeral 5 designates a receptacle, adapted to receive the castor, or the like, carried by the lower end of the leg 6 of a bed. This receptacle is preferably formed of glass, and its surfaces are polished or smooth, so that the bed bug cannot walk up the receptacle, except by walking up a relatively narrow strip or path 7, formed upon the outer surface of the receptacle. This 25 strip or path is rendered rough by any suitable means, so that the bed bug may readily walk up the same.

Formed integral with the receptacle 5, at one side thereof, is a vertical supporting element 8, which would also be formed of glass, with its surface polished or smooth, so that the bed bug cannot walk over the same. This supporting element has the roughened strip or path 7 continued over its outer face, as shown in Figure 3.

40 Arranged upon the outer face of the supporting element 8, Figure 3, are electrodes 9, formed of metal. The roughened strip or path 7 leads to the central portion of the lower electrode 9, as shown. The surfaces of these electrodes, near 45 their central portions, is also slightly roughened so that the bed bug may readily walk from one electrode to the other. The electrodes 9 are slightly spaced, and insulating material may be arranged between these electrodes, and the space 50 is such that a bed bug may reach from one electrode to the other and be thereby electrocuted. Wires 10 are secured to the electrodes and are connected with the opposite pole of a suitable source of current.

55 The numeral 11 designates a collecting recep-

tacle, which is arranged in close relation to the receptacle 5, and has a cut-away portion 12 to receive the shoulder or edge of the supporting element 8, while the adjacent portion of the collecting receptacle extends into a recess 13. It is thus 60 seen that the outer face of the supporting element 8 is disposed in substantial alignment with the inner face of the collecting receptacle, and the electrocuted bed bugs will fall into the collecting receptacle.

65 A cover 14 is provided for the supporting element 8, and this cover snugly fits upon such supporting element, at its ends, as clearly shown in Figure 1. This cover is preferably formed of insulating material. The cover has a band 15 70 secured thereto near its lower end, and this band has pivotal connection at 16, with a yoke 17, adapted to be swung over the upper end of the collecting receptacle, thereby serving to detachably connect the two receptacles.

75 Openings 18 are provided whereby the yoke may be moved upwardly.

The operation of the device is as follows:— With the various parts assembled as shown in Figure 1, a bed bug, in seeking to pass from the 80 floor to the bed, walks up the roughened strip or path 7, and reaches the electrodes 9, and in attempting to pass from one electrode to the other, it is electrocuted. The electrocuted bed bug now falls into the receptacle 11. By arranging the 85 lower end of the leg of the bed or castor within the receptacle 5, this receptacle also serves as a protector for the floor. The receptacle 5, in Figure 4, omits the electrocuting device. I prefer to place the lower ends of the three legs of the 90 bed in the receptacle 5, of Figure 4, while receptacle 5 of Figure 1 receives a fourth leg of the bed. The receptacle 5 of Figure 4 has no roughened path, and all of the bugs must, therefore, walk up receptacle 5 of Figure 1. Of course, the 95 invention is not necessarily restricted to this procedure, as any number of the receptacles 5, shown in Figure 1, could be used.

Having fully described my invention, what I claim as new is:—

100 1. A vermin destroyer, comprising a receptacle for receiving the lower end of the leg of a bed and having its outer surface smooth except for a roughened path, a supporting element mounted upon the upper portion of the receptacle at one 105 side thereof and having the roughened path continued thereon, spaced electrodes carried by the supporting element with one electrode having the roughened path leading thereto, means for connecting the electrodes to the opposite pole of 110

a source of current, and a collecting receptacle arranged near the first-named receptacle for receiving the electrocuted vermin as they fall from the electrodes.

5 2. A vermin destroyer, comprising a receptacle for receiving the leg of a bed and having its outer surface smooth except for a roughened path, a supporting element carried by the receptacle, and having the path continued thereon, spaced 10 electrodes carried by the supporting element and having the path leading to one electrode, and means for connecting the electrodes with the opposite poles of a source of current.

15 3. A vermin destroyer, comprising a receptacle to receive the lower end of the leg of a bed having its outer surface smooth except for a

roughened path, a supporting element carried by the upper portion of the receptacle near one side thereof and having the roughened path extending thereon, spaced electrodes carried by the supporting element and having the roughened path leading to one electrode, means for connecting the electrodes with the opposite poles of a source of current, a cover mounted upon the supporting element, a collecting receptacle arranged near the first-named receptacle and having a portion thereof disposed beneath the supporting element so that the electrocuted bed bugs will fall into the collecting receptacle, and means for detachably connecting the cover and the collecting receptacle.
